[57] CLAIM

The ornamental design for a combined needle recapping tray and lid, as shown and described.

DESCRIPTION

FIG. 1 is a perspective view of a combined needle recapping tray and lid showing my new design with the lid removed;

FIG. 2 is a perspective view thereof with the lid attached;

FIG. 3 is a top plan view of the tray;

FIG. 4 is a bottom plan view of the tray;

FIG. 5 is a side elevational view of the tray, the opposite side elevational view being identical thereto;

FIG. 6 is an end elevational view of the tray, the opposite end elevational view being identical thereto;

FIG. 7 is a top plan view of the lid;

FIG. 8 is a bottom plan view of the lid;

FIG. 9 is a side elevational view of the lid, the opposite side elevational view being identical thereto; and,

FIG. 10 is an end elevational view of the lid, the opposite end elevational view being identical thereto.
